CHARLES SPENCER, OF HAMILTON, ONTARIO, CANADA.

SANDING DEVICE FOR RAILWAYS AND THE LIKE.

1,404,904.

Specification of Letters Patent. Patented Jan. 31, 1922.

Application filed July 22, 1921. Serial No. 486,832.

To all whom it may concern:

Be it known that I, CHARLES SPENCER, a subject of the King of Great Britain, and a resident of the city of Hamilton, county of 5 Wentworth, Province of Ontario, Dominion of Canada, have invented certain new and useful Improvements in Sanding Devices for Railways and the like, of which the following is a specification.

10 My invention relates to improvements in sanding devices for railways and the like of the general type described in my co-pending United States application Serial No. 442,769 filed on February 5th, 1921, and the 15 object of the present invention is to provide an improved form in which the device may be made whereby certain weaknesses of the former construction are overcome, thus increasing the efficiency of the device and also 20 rendering the operation more reliable.

My invention consists of a sand container having the sides thereof tapering inwardly towards the bottom and provided with an orifice in the bottom thereof, an open ended 25 tubular casing secured to the container and engaging said orifice, said casing comprising an open ended vertically disposed cup portion extending upwardly into the container, said cup tapering inwardly towards 30 its lower open end, means for producing a downwardly directed suction through the cup, and a cone shaped cap loosely and resiliently supported above the upper end of the cup, the apex of said cone directed upwardly, all as hereinafter more particularly 35 described and illustrated in the accompanying drawings in which;

Fig. 1 is a central vertical section of my improved device, a portion of the pipe connection leading therefrom being broken away intermediately to economize space.

Fig. 2 is a bottom plan view of a cone shaped cap used in my invention showing the supporting springs and locating fingers 45 carried thereby.

Fig. 3 is an enlarged fragmentary view of a portion of Fig. 1 showing the air connections of the device and also a pressure regulating plug.

50 Fig. 4 is an end view of this pressure regulating plug.

Like characters of reference indicate corresponding parts in the various views.

1 is the sand container, the side walls 2 of which taper inwardly towards the bottom 55 3, the bottom having the orifice 4 therein.

5 is an open ended tubular casing constituting a suction member.

The upper portion of the casing 5 is cylindrical and carries the flange 6, and 7 and 8 60 are portions of this upper cylindrical portion disposed respectively above and below the flange 6.

9 are bolts engaging orifices in the flange 6 and in the bottom 3 for securing the casing 65 5 in position on the container.

Within the casing 5 and extending downwardly from its upper end is formed the open ended cup 10. The upper section 10¹ of this cup is cylindrical. Extending downwardly from the cylindrical portion 10¹ is 70 an inwardly tapering portion 10².

11 is a depending cylindrical skirt carried by the casing 5 and extending downwardly from the lower end of the tapering portion 75 10² of the cup 10. This skirt is concentric with and is in spaced relation to the internal bore 12 of the casing, which is cylindrical at this section, thus an annular chamber 13 is formed surrounding the skirt 11, said 80 chamber being closed at its upper end and constituting at its lower end an annular nozzle 14 surrounding the lower end of the skirt 11.

The walls of the annular chamber 13 being 85 concentric, it follows that this chamber is of constant width throughout its length.

The interior of the skirt 11, it will be noted, forms a cylindrical portion 10³ of the cup 10 extending downwardly from the 90 lower end of the tapered portion 10².

The upper end of the annular chamber 13 is at the level of the bottom of the tapered portion 10² of the cup.

Extending downwardly from the nozzle 95 14 the bore of the casing 5 tapers outwardly as at 15 thus increasing the diameter of the bore of the casing towards the lower end thereof.

16 is a boss formed on the side of the casing and has the internally threaded orifice 17 extending therethrough and communicating with the top of the annular chamber 13.

The inner end of the orifice 17 is tapered at 17¹ for a purpose as will appear herein- 105 after.

18 is a pressure regulating plug threaded externally to engage the threaded orifice 17 and is provided with an axial orifice 18¹ extending therethrough.

5 19 is a pressure pipe carrying compressed air or steam and is threaded to engage the orifice 17.

10 20 is a valve in the pipe 19 and would be situated to be operated by the motorman or engineer, 20¹ being the operating handle of the valve.

15 The lower end of the casing 5 is threaded at 21 to receive a suitable pipe 22, the lower end of which is situated directly above the rail 23.

20 24 is a cone shaped cap resiliently supported upon the upper end of the casing 5 by means of the bent springs 25. There are three of these springs spaced equally about the cone and being secured to the inner face of the cone by the rivets 25¹.

25 26 are locating fingers spaced equally about the cone and secured to the inner face thereof by the rivets 26¹.

30 25 These fingers extend downwardly from the cone and engage the wall of the cylindrical portion 10¹ of the cup 10 being so disposed that a certain degree of lateral freedom is permitted to the cone.

35 30 The under edges 26² of the heads of the fingers 26 lie in the plane of the base of the cone for a purpose as will hereinafter appear.

24¹ is the apex of the cone.

35 35 The construction and operation of my invention is as follows:

40 The casing 5 is mounted in the sand container by passing it downwardly through the orifice 4 so that the cylindrical portion 8 engages the orifice. It is then secured in place by the bolts 9. The length of the boss 16 is such that the casing can be passed downwardly through the orifice 4.

45 45 The cone 24 is engaged with the upper end of the casing so that the locating fingers 26 pass into the cup 10 and the springs 25 engage the upper edge of the casing. (See Fig. 1.)

50 50 The pressure regulating plug 18 is screwed into the orifice 17 and its inward travel is limited by the tapered portion 17¹ of the orifice.

55 The pipe 19 carrying the pressure fluid, such as compressed air or steam is then connected.

The pipe 22 is engaged with the lower threaded portion of the casing 5.

60 Consider now the container to be filled with sand.

65 Normally when the device is inoperative the sand will not enter the cup 10, but will lie at rest on an inclined surface extending from the edge "A" at the base of the cone to the outer top edge "B" of the casing.

65 This line is indicated in Fig. 1.

If now the valve 20 be opened by the motorman, a current of compressed air will rush through the pipe 19 and orifice 18¹ in the plug 18 into the top of the annular chamber 13, then pass downwardly through 70 this chamber and in rushing past the nozzle 14 will create a partial vacuum at the bottom of the skirt at "C".

This will induce, by suction, a current of air to pass downwardly from the container 75 and through the cup 10, that is a downwardly directed suction will be created in the cup 10.

This suction will immediately draw sand from the container into the cup and due to 80 the peculiar shape and proportion of the cup, it will quickly be filled and when the valve 20 is closed the sand in the cup will flow downwardly by gravity from the member 5 through the pipe 22 to the rail 23 upon 85 which it will be quietly deposited.

In former sanding devices it has been found that great difficulty has been caused by the packing of the sand thus causing it to cake, interfering seriously with the flow 90 and in many cases stopping it altogether.

The overcoming of this has been one of the chief objects of my present invention and has been primarily accomplished by the cone-shaped cap 24 and the method of 95 mounting it.

This cap is freely supported on the cup and may slide laterally a certain amount since the locating fingers 26 permit this freedom.

100 Further the springs 25 render the supporting of the cone resilient and therefore during the operation of the device whenever the suction is produced the cone moves downwardly and when the suction is released it again moves upwardly. The edges 26² of the fingers 26 limit the downward movement of the cone.

105 Also the passage of the car over the rough road bed or over the rail joints will cause the cap to shake about over the top of the cup.

110 This vibrating action of the cone taken in conjunction with its sharp conical shape provides a means of keeping the sand about 115 the cone loose and free flowing as the sharp pointed apex of the cone practically cuts its way through the sand.

115 Further the locating fingers 26 being made of thin strips of metal form knives which 120 tend to cut any lumps of sand as they pass inwardly towards the cup. Also the spaced springs 25 and fingers 26 (see Fig. 2) constitute a form of strainer which would stop any such lumps from entering the cup and 125 clogging the device.

120 In my improved device it will be noted that the sand is drawn into the cup by suction but flows from the cup to the rail by gravity and also that a perfectly clear un- 130

obstructed straight passageway is provided through the device thus rendering the clogging of the device practically impossible. Further the cap 24 is not fastened in any way to the remainder of the device but may be freely lifted out by hand.

This is a most important feature since it enables the sand to be deposited quietly upon the rail with no tendency of being blown off by the current of air.

The provision of the pressure regulating plugs 18 permit any one device to be adapted to any pressure, since a number of these plugs would be supplied each having a different sized orifice 18¹ and by fitting the correct plug, the pressure in the supply pipe 19 may be throttled down so as to produce the desired operating pressure in the annular chamber 13. It will readily be seen that this will provide a means of at all times operating the device under the most economical and efficient conditions and that these plugs 18 virtually constitute economizers.

25 While, of course, the device might be operated continuously by holding the valve 20 open thus causing a continuous suction through the cup with a continuous flow of sand, it is not intended that the device be operated in this manner since a more economical and efficient operation is obtained by the intermittent opening and closing of the valve.

When the valve is held open continuously 35 the sand does not pass from the cup to the rail entirely by gravity but is partly blown by the current of air from the nozzle.

In this case however, due to the peculiar shape of the cup 10 whereby it tapers inwardly towards its bottom end it has been found that the stream of sand flowing from the bottom of the cup has a throttling effect on the current of air passing through the portion 15 of the casing and therefore 45 the action of this current of air in blowing the sand towards the rail is considerably reduced from that existing in former devices and thus a quieter delivery of the sand upon the rail is obtained.

50 It is intended that the valve 20 be operated intermittently thus creating an intermittent instead of a continuous suction.

In this case the operation is as follows.

It has been found by experiment that the 55 sand is drawn most rapidly into the cup during the initial moments of the action of the suction. Therefore, when the valve 20 is first opened and the downward suction is produced in the cup the maximum pull is exerted on the sand and the sand is therefore drawn most rapidly into the cup during this initial period.

Owing to the peculiar shape of the cup with its restricted lower portion, it very 60 rapidly fills with sand, which sand after

the valve 20 is closed flows by gravity to the rail.

The valve 20 would be opened and closed intermittently thus producing a series of intermittent suction impulses. At each impulse the cup 10 would be filled with sand, the period during which the sand flows from the cup to the rail coinciding with the period during which the valve is closed so that at this time there is no current of air flowing through the nozzle and therefore there is no blowing of the sand to the rail but it flows entirely by gravity.

In this construction there are no baffles or turns in the pipes carrying the sand to the rails and therefore no tendency to become clogged up.

In mounting the device on the container, a tight joint would be made at the connection of the portion 8 with the orifice 4 in order to prevent any moisture which would be thrown up by the wheels of the car from creeping up past this joint into the interior of the container.

Owing to the shape of the annular chamber 13, it will clear itself and there will be no likelihood of particles of rust or such like clogging the nozzle 14.

From the foregoing it will be noted that I have devised valuable improvements in sanding devices which will greatly increase their economy and efficiency.

What I claim as my invention is:

1. In a sanding device for railways and the like, the combination with the sand container and the sand therein, of an open ended tubular casing communicating with the interior of the container, means for producing a suction within said tubular member, and a cone shaped cap loosely and resiliently supported within the container above the open end of the tubular casing.

2. In a sanding device for railways and the like, the combination with the sand container and the sand therein, of an open ended tubular casing communicating with the interior of the container, a cone shaped cap supported within the container above the upper open end of the tubular casing, and means for permitting raising and lowering of the cone shaped cap slightly upon the operation of the device.

3. In a sanding device for railways and the like, the combination with the sand container and the sand therein, of an open ended tubular casing communicating with the interior of the container, a cone shaped cap loosely and resiliently supported within the container above the upper open end of the tubular casing, and means for permitting raising and lowering of the cone shaped cap slightly upon the operation of the device.

4. In a sanding device for railways and the like, the combination with the sand container, of an open ended tubular casing com-

municating with the interior of the container and extending upwardly thereinto, the upper portion of said casing constituting an open ended cup, a concentric annular 5 chamber surrounding the lower portion of said cup, the annular chamber being closed at its upper end and forming at its lower end an annular nozzle surrounding the lower open end of the cup, a pipe communicating 10 with the upper closed end of the annular chamber, a valve in said pipe, and a cone-shaped cap loosely and resiliently supported within the container above the upper open end of the tubular casing.

15 5. In a sanding device for railways and the like, the combination with the sand container, of an open ended tubular casing communicating with the interior of the container and extending upwardly thereinto, 20 the upper portion of said casing constituting an open ended cup, said cup comprising an upper cylindrical portion, an intermediate inwardly tapering portion and a lower cylindrical portion of the diameter of the 25 smaller lower end of the tapering portion, a concentric annular chamber surrounding the lower cylindrical portion of the cup, the annular chamber being closed at its upper end and forming at its lower end an annular nozzle 30 surrounding the lower open end of the cup, a pipe communicating with the upper closed end of the annular chamber, a valve in said pipe, and a cone-shaped cap loosely and resiliently supported within the container above the upper open 35 end of the tubular casing.

6. In a sanding device for railways and the like, the combination with the sand container, of an open ended tubular casing communicating with the interior of the container and extending upwardly thereinto, the upper portion of said casing constituting an open ended cup, said cup comprising an upper cylindrical portion, an intermediate 40 inwardly tapering portion and a lower cylindrical portion of the diameter of the smaller lower end of the tapering portion, a concentric annular chamber surrounding the lower cylindrical portion of the cup, the annular chamber being closed at its upper end and forming at its lower end an annular nozzle 45

50

surrounding the lower open end of the cup, the tubular casing extending below said nozzle and the bore thereof tapering outwardly from said nozzle to the lower end of the casing, the casing provided with a passageway communicating with the upper closed end of the annular chamber, pressure reducing means in said passageway, an inlet pipe engaging the outer end of said passageway, a shut off valve in said pipe, and a cone-shaped cap loosely and resiliently supported within the container above the upper open end of the tubular casing.

7. In a device of the class described a hollow cone-shaped cap, depending fingers secured to the inner face of the cone along the lower edge thereof and equally spaced about the circumference, bent spring strips secured to the inner face of the cone along its lower edge and equally spaced about the circumference between the aforesaid depending fingers, said spring strips being bent outwardly and inwardly in U-shape.

8. In a sanding device for railways and the like, the combination with the sand container, of an open ended tubular casing communicating with the interior of the container and extending upwardly thereinto, means for producing a downwardly directed suction through the tubular member, a hollow cone-shaped cap, depending fingers secured to the inner face of the cone along the lower edge thereof and equally spaced about the circumference, bent spring strips secured to the inner face of the cone along its lower edge and equally spaced about the circumference between the aforesaid depending fingers, said spring strips being bent outwardly and inwardly in U-shape, said cone-shaped cap supported within the container above and in spaced relation to the upper open end of the tubular casing, the depending fingers extending freely down into the interior of the casing and the under faces of the U-shaped springs freely resting on the top edge of the tubular casing.

CHARLES SPENCER.
